UNITED STATES PATENT OFFICE.

HORACE WADE ARNOLD, OF VANCOUVER, WASHINGTON.

MAGNETIC ORE-SEPARATOR.

1,362,072.

Specification of Letters Patent. Patented Dec. 14, 1920.

Application filed November 17, 1917. Serial No. 202,483.

To all whom it may concern:

Be it known that I, HORACE WADE ARNOLD, citizen of the United States, residing at Vancouver, in the county of Clarke and State of Washington, have invented certain new and useful Improvements in Magnetic Ore-Separators, of which the following is a specification.

This invention relates to magnetic ore separators, and more particularly that type comprising a drum adapted to revolve in the path of travel of a liquid holding in partial suspension the magnetic and non-magnetic bodies desired to be separated.

One of the objects of the present invention is to provide a simple, practical magnetic separator of the above general character which will be reliable in use and operation. A further object is to provide an apparatus of the above character which may be easily controlled and adjusted, whereby the magnetic bodies are more easily and accurately separated according to their magnetic qualities.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof, all as more completely outlined herein.

To enable others skilled in the art so fully to comprehend the underlying features of this invention that they may embody the same by the numerous modifications in structure and relation contemplated by this invention, drawings depicting a preferred form have been annexed as a part of this disclosure, and in such drawings, like characters of reference denote corresponding parts throughout all the views; in which

Figure 1 is a perspective view showing the complete apparatus;

Fig. 2 is an end elevation thereof;

Fig. 3 is a transverse sectional view on the line 3—3 of Fig. 5;

Fig. 4 is a semi-diagrammatic view showing the manner in which the revolving drum is electrically wound;

Fig. 5 is a longitudinal sectional view taken on line 5—5, Fig. 4;

Figs. 6 and 7 are detail views at right an-

gles to each other showing the electrical terminal connections.

Referring now to the drawings in detail, and more particularly to Fig. 1, 11 represents a drum mounted on a shaft 12 driven by pulley 12' and supported in end bearings 13 trunnioned in legs or other suitable framework adapted to support the magnetic drum 11 adjustably by means of screws 15. The lower half of the drum rests in a trough 16 of non-magnetic material having an inlet apron 18 at one side and an outlet apron 20 at the other. Within the drum are disposed a plurality of electro-magnets 25 having suitable connections whereby the drum is magnetized during a portion of its revolution as will be hereinafter more fully explained. A suitable fluid, such as water containing the finely ground ore, is admitted over the apron 18 adjustably positioned by means of set screw 19 at one side of the drum, as shown in Figs. 2 and 3, and thence passes under the drum and out the opposite side over the spill-way 20 adjustably set by screws 21.

At the bottom of the trough there are provided two discharge openings adapted to be closed by sliding gates 22 and 38 held respectively in adjusted position by means of set screws 23 and 39 respectively. Between these gates which may be opened and closed to any desired degree is a vertically disposed partition 36 mounted upon end trunnions 37, whereby the same may be tilted from one side to the other as desired. If deemed necessary one or more other gates may be provided in the trough as indicated at the point 17. It will thus be seen that as the liquid containing the magnetic bodies enters over the intake apron 18 the revolving drum will pick up the magnetic bodies and carry the same around until removed by a scraper 43 held in adjusted position by set screws or bolts 45 against a transverse frame 44 supported at its ends by arms 41 from pivots 42. The non-magnetic bodies will pass out through the opening provided by the gate 22 and fall preferably upon the buckets on an endless conveyer therebelow not shown in the drawings. The bodies responding only feebly to magnetic attraction and which will not adhere to the drum against the action of gravity will be carried partly up toward the scraper 43 and then fall back and pass out through the opening 105.

closed by the gate 38 onto a second conveyer not shown. The provision of the door 17 permits the collection at that point of bodies having a greater affinity for the magnets than those last described, but not such an affinity as will cause them to be carried up to the scraper 43. In this manner the several grades of magnetic and non-magnetic material are accurately separated and 10 collected.

Referring now to the drum as shown more clearly in Figs. 3 and 5 it is to be noted that this comprises a frame-work 24 of non-magnetic material upon which are mounted rows 15 of electro-magnets 25 arranged in two series 26 and 27 longitudinally parallel with the axis of the drum and attached to the frame, so that they are held securely in place. Each series of these electro-magnets is connected in the same electric circuit, the magnets of one series being of one polarity and the magnets of the other series having opposite polarity.

By reference to Figs. 6 and 7 it will be seen that a ring or collar 32 is securely and permanently attached to the frame on which the magnets are mounted. It will be observed that the upper terminals of the series of magnets 26 are connected to the ring 32, while the lower terminals of the series of magnets 27 are also connected to the ring. The lower terminals of the series 26 are connected to respective segments 35 of a commutator, while the upper terminals of the series 27 are connected to alternate commutator segments 35. An arc shaped brush 34 is carried by the bearing 13 and is designed to be engaged by the commutator segments 35 as the latter rotate. The brush 34 is connected with one side of a source of current (not shown) while the brush 33 engages the ring 32, as shown in Fig. 1, and is connected to the opposite side of the source of current. The brush 34 may be shifted either to the right or left in any desired manner, to control the magnets with which it is in electrical contact through the blades 35, thereby regulating the time of magnetization of the series.

50 Thus by reference to Fig. 6 it will be seen that the adjustable member 34 engages less than half of the blades 35, and by reference to Fig. 4 it will be seen that when so connected only the lower portion of the magnets 55 in the magnetic drum will be magnetized. It is of course, to be understood that this drum 11 is made of suitable non-magnetic material such as zinc and is of water-tight construction.

60 In Fig. 4 it will be seen that the poles of the magnets are shown slightly separated by insulation to avoid short circuiting. These poles of the magnets are cast or made rectangular in form so that when the electro-magnets are placed in position on the frame-

work of the drum the poles will present a continuous surface around the entire drum, separated of course only by the insulation.

It is believed that the construction and operation of this device will be clear from 70 the above description and a brief statement of the operation thereof is as follows:

A novel and important feature of this device is that the process of separation of the heads from the tails is carried on while the 75 materials to be separated are submerged in water, for the buoyancy of the water operates to give to the particles greater freedom to separate from each other and become disentangled from each other than would be 80 the case if it were not for the water. In operating this device, the drum is rotated in the direction of the arrow, so that the side of the drum next to where the water and material is fed in travels downwardly. The 85 mixture to be separated is mingled with water as it is delivered into the machine over apron 18, so that the material is scattered evenly across the entire face of the magnetic drum 11, as the water and material 90 flow against the drum.

The current of the water, as it comes against the drum should have substantially the same velocity as the rotation of the drum, and the flow should be sufficient to 95 wash the heads out on the delivery side, but not to wash the tailings out of the bottom. The speed and volume of the flow is regulated by proper appliances where the water and the materials to be separated are mixed. 100

The particles to be separated by this contrivance being mixed with water as they are fed into it and submerged by it, by reason of the buoyancy of the water, more easily move in the direction in which they may be 105 attracted.

The sliding apron 18 is adjusted so as to bring the water and material mixed with it close up to the drum, the distance therefrom being varied to suit the size of the material 110 to be separated and the quantity fed into it. The same explanation applies to the sliding apron 20 on the delivery side, with reference to the heads, and also with reference to the sliding doors or gates 22 and 38 at the bottom of the trough. These various aprons or sliding gates are provided with set screws as above explained to hold them in position when they are once adjusted.

The magnetic drum as it rotates is 120 brought in close proximity to every particle that is fed against it, and the brush on the commutator is so adjusted that each successive electro-magnet as it travels downwardly during the rotation of the drum is 125 magnetized as it reaches a predetermined point with respect to the water line adjacent the apron where the material is fed. It is to be noted that the brush on the commutator should be so adjusted that the mag- 130

net winding on the intake side will not cut in until after the magnets have passed below the water line. It is quite important in obtaining a proper sorting of the material 5 to allow them a free drop from the inlet apron 18 before the materials are subjected to the magnetic attraction. An earlier excitation of the magnets would tend to cause the material fed against the drum to pile 10 up and some of the tails would inevitably be entangled among the heads and held there during the complete circumference traveled by the materials to the outlet apron. It is therefore advisable that the excitation 15 of the magnets take place sufficiently below the water line to give the material a free drop from the edge of the apron before it is subjected to magnetic attraction.

The electro-magnets exert their magnetic 20 power through the skin or water-jacket which surrounds the electro-magnetic drum, and the particles of the materials to be separated that are subject to the magnetic attraction are drawn up against the drum, and 25 are held thereagainst as the drum rotates downwardly following the current of the water. The magnetic attraction holds the particles against the face of the drum as the drum rotates and carries them around 30 to the point of delivery, and the non-magnetic particles drop away by the force of gravity into the trough, then through the openings provided at the bottom as tailings, which may be removed by buckets on an 35 endless chain conveyer or some other convenient method.

The particles that are sufficiently magnetic to be carried up by the magnets against the force of gravity to the delivery 40 apron 20 are there removed by the scraper 44, brush 34 at that point uncovering the respective blade of the commutator connected with the electro-magnet at that point adjacent the scraper.

45 As the drum rotates, the magnetic particles that are attracted are carried at first in the same direction in which the force of gravity operates, so that the operation of the force of gravity and the action of the 50 machine coincide; but as soon as the particles reach the lowest point of the rotation of the drum they are then lifted against the force of gravity. Here is where the parting strip or division slide 36 becomes operative.

55 There are some finely divided mineral substances found in certain ores and sands that are not strong enough magnetically to be held and lifted up on the far side of the drum against the force of gravity, and 60 hence will fall away and drop on the opposite or far side of this parting strip 36, and so are sorted from the tailings which fall on the near side of the parting strip and which have no magnetic attraction at all.

65 By this means the particles of ore or me-

tallic substances which may be strongly magnetic are held firmly against the face of the magnetic cylinder as it rotates, until reaching the point of delivery where they are released by the cessation of the magnetic 70 attraction, they are then carried over the delivery spout by the flow of water into a proper receptacle. The non-magnetic particles fall to the bottom of the trough on the near side of the parting strip. They 75 are drawn away through the opening at the bottom as tailings, with such a flow of water as may be permitted to pass through that opening, but those of such low magnetic susceptibility as are not held by the attraction 80 of the magnets of the cylinder against the force of gravity on the rise, fall on the far side of the parting strip and are sorted out.

Under all circumstances, the height of 85 the water in the trough should be kept so that it flows over the delivery end into the delivery spout. If the water is not kept up to that level the heads as they are delivered at the delivery end will not be thrown over 90 into the proper place.

The intensity of the magnetic attraction exerted by the magnetic cylinder may be regulated by making an appropriate alteration in the strength of the electrical current that is delivered to the magnet windings. That is, if it is desired to increase the magnetic attraction of this cylinder, so as to hold with a stronger attraction particles which may be magnetically susceptible 95 only in a slight degree, the electrical current is correspondingly increased.

It may also be noted that a better sorting of the materials is obtained when submerged 105 in water or other liquid whereby the buoyant properties of the liquid assist in the operation by giving greater freedom to the particles to move in response to the attractions of gravity and also the force exerted thereon by the magnets. This arrangement 110 also enables the magnetic force exerted by the magnets to hold the materials of weak susceptibility to magnetization more evenly and deposit them in separate compartments as previously explained which could not be 115 done unless the materials were acted upon by the buoyancy of the liquid. For example hematite and platinum are feebly susceptible to the magnetic attraction and both can be separated from beach and river sand 120 only with the assistance of the buoyancy of water. In fact the greater the density of the liquid in which the material is submerged the more successful is the operation. Thus sea water is much more efficient than 125 fresh water.

The capacity of this machine to handle a larger or smaller quantity of material, may be increased or diminished by increasing the revolutions of the cylinder up to a certain 130

point, and also by building the cylinder longer. The machine may be made with a short cylinder of only a few inches diameter and a few feet in length, or it may be made 5 with a cylinder larger in diameter and many feet long. Its capacity can be enormously increased by these two methods.

Of course the increasing for capacity by increasing the revolutions of the cylinder has 10 certain limitations and the feature of centrifugal force must necessarily be taken into consideration. In other words to make the operation successful with an increased speed of revolution the electrical current put 15 through the magnets must be correspondingly increased, but even then this correlation reaches the limit beyond which the speed cannot go. This however would be clear to those skilled in the art and experiments 20 would shortly determine the maximum speed at which the drum could be revolved with the desired degree of efficiency.

It is thus seen that the present invention is believed to accomplish among others all 25 of the objects and advantages herein set forth.

I realize that considerable variation is possible in the details of construction and arrangement of parts without departing 30 from the spirit of my invention, and I therefore do not intend to limit myself to the specific form shown and described.

Having thus described my invention what I claim as new and desire to secure by Letters Patent is:

1. In a magnetic separator in combination, a magnetic drum having a plurality of magnets therein adapted to attract material to the drum, a water-tight casing inclosing said 40 magnets, a trough in which said drum is adapted to revolve, an adjustable inlet apron by means of which water and material are introduced to said trough and an outlet by means of which water and material are discharged, said aprons being arranged at opposite sides of the trough, and means for 45

removing the tailings from the bottom of said trough, said means including an adjustable gate and a partition adjacent the gate adapted to separate the tailings from 50 particles having only slight affinity for the magnetic attraction, and an adjustably mounted scraper adjacent the outlet apron.

2. In a magnetic separator, a drum, a shaft supporting the drum, means for rotat- 55 ing the shaft, a plurality of rows of magnets within said drum, a ring secured to the drum, the upper terminals of alternate rows of magnets being connected with said ring, the lower terminals of the remaining rows of 60 magnets being connected with said ring, stationary bearings for said shaft, a commutator carried by the shaft and rotatable therewith, and being provided with projecting insulated segments, each of the rows of 65 magnets being connected to one of the segments, and the brush arranged to engage a plurality of segments simultaneously.

3. In a magnetic separator, a drum, a shaft supporting the drum, means for rotat- 70 ing the shaft, a plurality of rows of magnets within said drum, a ring secured to the drum, the upper terminals of alternate rows of magnets being connected with said ring, the lower terminals of the remaining rows 75 of magnets being connected with said ring, stationary bearings for said shaft, a commutator carried by the shaft and rotatable therewith, and being provided with projecting insulated segments, each of the rows of 80 magnets being connected to one of the segments, and an arc shaped brush concentric with said commutator and adjustable to different positions, said brush being arranged to engage a plurality of segments simulta- 85 neously.

In testimony whereof I affix my signature in presence of two witnesses.

HORACE WADE ARNOLD.
